MICHAEL RIESNER, OF CINCINNATI, OHIO, ASSIGNOR TO WORTHINGTON PUMP AND MACHINERY CORPORATION, OF NEW YORK, N. Y., A CORPORATION OF VIRGINIA.

VARIABLE-CAPACITY COMPRESSOR.

Application filed September 17, 1926. Serial No. 136,009.

This invention relates to means for unloading fluid compressors and broadly to means for automatically unloading the compressor, gradually, when the receiver pressure rises 5 to pre-determined points and gradually loading it as the receiver pressure falls, and the primary object of the invention is to provide an apparatus of this type which shall be economical in operation, provide a relatively 10 high efficiency compressor, and one which will be relatively simple in construction and consequently cheaper to manufacture than those heretofore used.

The present invention contemplates the use 15 in a variable capacity compressor, of clearance chambers and a by-pass port connected in series which permit, with the other mechanism, the gradual unloading and loading of the compressor cylinder for permitting its 20 operation under various pre-determined percentages of its full capacity.

For a full understanding of the invention, 25 a detailed description of a construction embodying the same in a preferred form will now be given in connection with the accompanying drawing forming a part of this specification and which shows in section and partly in elevation a variable capacity compressor and its regulator or control constructed in accordance with this invention, 30 and the features forming the invention then specifically pointed out in the claims.

Referring more particularly to the drawing, A is the compressor cylinder, B the piston 35 and C the piston rod which is driven in any suitable manner, and while no suction or discharge valves are shown in the drawings it is to be understood that the compressor is provided with suction and discharge valves, of 40 approved type, at the crank and head ends of the cylinder A as is usual in the construction of double acting compressors of approved types.

A clearance chamber 1 is provided at the 45 head end of the cylinder A and a second clearance chamber 2 is positioned contiguous to the clearance chamber 1 and has direct communication with a by-pass port 3 which extends along the cylinder A to the crank end 50 thereof.

The clearance chamber 1 has communication 55 with the interior of the cylinder A through a port 4 which is controlled by a valve 10 actuated by a pressure-operated pis-

ton 11 which is moved in its cylinder 12 by receiver pressure to open the valve for connecting the cylinder with the clearance chamber 1 and partial unloading and is closed by spring 13. Fluttering of the valve 10 is prevented by the spring 14 which engages the 60 piston 11 on its side opposite from that engaged by the closing spring 13.

The clearance chamber 2 is connected to the clearance chamber 1 by a port 21 which is closed by a valve 22, and has direct connection 65 with the by-pass port 3. The by-pass port 3 has connection with the interior of the cylinder A at the crank end of the cylinder, through a port 30 which is controlled by a valve 31. The valves 22 and 31 are actuated 70 by pressure-operated pistons 23 and 33 respectively which are moved by receiver pressure to open the valves to partial and complete unloading of the cylinder A and are closed by springs 24 and 34 respectively.

The pistons 11, 23 and 33 are automatically controlled by the control apparatus D and pressure is applied to the inner side of the piston 11, through the passageway 15, to open the clearance valve 10 for the first unloading step, 80 by receiver pressure transmitted through the pipe 1^a. Pressure is applied to the inner side of the piston 23 through the pipe 2^a to open the valve 22 for the second unloading step, and receiver pressure is applied to the inner side of the piston 33 through the pipe 3^a for opening the valve 31 for the third or final unloading 85 step at which time the compressor will operate at zero capacity.

Admittance of pressure to the pipe 1^a, 2^a and 3^a and consequently to the pistons 11, 23 and 33 is controlled for unloading and loading, by a piston valve 40, which is actuated by apparatus controlled by the receiver pressure, as usual in such unloading devices, and this receiver pressure and operation of the valve 40 is preferably secured through a pressure operated piston 41 controlled by a pilot valve 42. The pilot valve 42 is controlled by the pivoted, weighted lever 43 which is in turn controlled by the diaphragm 44 actuated by receiver pressure entering the chamber 45 through the inlet 46, and thus the pilot valve 42 is controlled directly by receiver pressure 90 to control the flow of pressure fluid for actuating the piston 41. The pilot valve 42 is controlled by the diaphragm 44 actuated by receiver pressure entering the chamber 45 through the inlet 46, and thus the pilot valve 42 is controlled directly by receiver pressure 95 to control the flow of pressure fluid for actuating the piston 41. The pressure fluid used for operating the piston 41 may be of any suitable character and taken from any suitable

source, thus enabling the apparatus D to be controlled by slight variations in the receiver pressure, while employing pressure as heavy as desired for actuating the piston 41. The 5 control apparatus just generically described is more fully illustrated and specifically described in my prior Patents numbered 1,579,781 and 1,579,782.

The clearance chambers may be of any 10 desired capacity so as to unload and load the cylinder in the steps required, but assuming that the capacity of each clearance chamber is such as to provide a one-third unloading of the cylinder, the operation of the construction shown and above described, is as follows: Assuming that the compressor is operating at full capacity, an increase in receiver pressure above that for which the apparatus is set will raise the lever 43 and operate the 15 pilot valve 42 so as to admit pressure fluid through the passage 47 against the right end of the piston 41 and connect the other end of the cylinder 48, in which the piston 41 moves, with the exhaust 49, and thus move 20 the piston 41 to the left, in the drawing, until the cut off end 50 of the piston valve 40 passes the port of the pipe 1^a, when the fluid which is admitted to the cylinder 51, under receiver pressure, through the pipe 52, will 25 pass through the pipe 1^a to the inner side of the piston 11 and open the valve 10 to connect the compressor cylinder A with the clearance chamber 1, at which time the compressor will operate at 75% capacity. The 30 control apparatus now returns the pilot valve 42 to its normal position, preventing inlet to or exhaust from the cylinder 48 and stopping the piston 41 in this position.

On a further increase of receiver pressure 40 the same operation is repeated except that the piston valve is moved forward another step and opens up communication with the pipe 2^a to permit opening of the valve 22 by movement of the piston 23, which opens up 45 the clearance chamber 2 and by-pass port 3 to the clearance chamber 1 and through the chamber 1 to the cylinder A, thus fully unloading the head end of the cylinder A so that the compressor operates at 50% capacity.

50 On a still further increase of receiver pressure the same operation is again repeated, this time moving the piston valve 40 another step so as to permit the fluid under receiver pressure to flow through the pipe 3^a and move the piston 33 for opening the valve 31, thus opening the crank end of the cylinder A to the by-pass port 3 and through the chambers 2 and 1 to the head end of the cylinder for completely unloading both ends of the 55 cylinder so that the compressor operates at zero capacity.

Decrease in receiver pressure permits the weighted lever 43 to fall, and reverses the above operation, the compressor being gradually loaded in the same proportions of its

full capacity as those in which it is unloaded; i. e. upon the decrease in receiver pressure the piston valve 40 is moved one step to the right, in the drawing, and cuts off communication between the pipes 52 and 3^a and relieves the 70 piston 33 of pressure, the pressure fluid bleeding from pipe 3^a through the open end of the cylinder 51, which permits the spring 34 to seat the valve 31 and permits operation of the compressor at 50% capacity. 75

As the receiver pressure further decreases the piston valve 40 is moved to the right, in the drawing, to successively cut off flow of pressure fluid to pistons 23 and 11 and permit seating of the valves 22 and 10 and the 80 compressor then operates, first at 75% capacity while only the valve 22 is seated, and then at 100% or full capacity when the valve 10 is seated.

From the foregoing description taken in 85 connection with the accompanying drawing it will be apparent that the present invention provides an efficient variable capacity compressor of extremely simple construction in which the compressor cylinder is gradually 90 unloaded, and loaded by successive opening to and closing from the compressor cylinder of the clearance chambers 1 and 2 and by-pass port 3, and it will be noted by reference to the drawing that the clearance chamber 2 95 is in fact a part of the by-pass port 3 and that the latter operates as a clearance chamber when only the valves 10 and 22 are open, coming into operation as a by-pass port when the valve 31 is opened. 100

The cylinders in which the pistons 11, 23 and 33 operate may be connected by a pipe 36 to a low pressure such as the intercooler pressure in a multiple stage compressor.

It will be understood that the invention is 105 not limited to the specific form or arrangement of parts illustrated, but that many modifications may be made therein while retaining the invention defined by the claims.

What is claimed is:

1. In a variable capacity compressor, the combination with a cylinder, of a plurality of clearance chambers in the head end of the cylinder, a passage connecting one or more of said clearance chambers with the crank end 115 of the cylinder, and pressure controlled means for partially unloading the head end of said cylinder by one of said chambers, wholly unloading the head end by the clearance chambers, and wholly unloading the cylinder by 120 said clearance chambers and passage.

2. In a variable capacity compressor, the combination with a cylinder, of a clearance chamber at the head end of the cylinder, a by-pass port extending along the cylinder and having connection at its opposite ends with said clearance chamber and the crank end of the cylinder respectively, and pressure controlled means for partially unloading the head end of the cylinder by said clearance 130

chamber and fully unloading the head end of the cylinder by said clearance chamber and by-pass port.

5. In a variable capacity compressor, the combination with a cylinder, of a clearance chamber at the head end of the cylinder, a by-pass port extending along the cylinder and having connection at its opposite ends with said clearance chamber and the crank end of 10 the cylinder, pressure controlled means for partially unloading the head end of the cylinder by said clearance chamber and fully unloading the head end of the cylinder by said clearance chamber and by-pass port, and unloading the crank end of the cylinder by said 15 by-pass port.

4. In a variable capacity compressor, the combination with a cylinder, of means for gradually unloading the cylinder comprising 20 a clearance chamber at the head end of the cylinder and a by-pass port along the cylinder, and having connection at its opposite ends with said clearance chamber and the crank end of the cylinder and pressure operated means for partially unloading the head 25 end of said cylinder by said clearance chamber and wholly unloading the head and crank ends of the cylinder through said by-pass port and clearance chamber.

30 5. In a variable capacity compressor, the combination with a cylinder, of a plurality of clearance chambers in the head end of the cylinder, pressure operated means for open-

ing one of said chambers to said head end for partly unloading the head end, and pressure operated means for connecting said clearance chambers for further unloading said head end. 35

6. In a variable capacity compressor, a combination with a cylinder, of a plurality of 40 clearance chambers in the head end of the cylinder, pressure operated means for opening one of said chambers to said head end for partly unloading the head end, and pressure operated means for connecting said clearance 45 chambers for further unloading said head end, a passage connecting said second chamber with the crank end of the cylinder, and pressure operated means controlling connection of said passage and crank end. 50

7. In a variable capacity compressor, the combination with a cylinder, of a clearance chamber in the head end of the cylinder, pressure operated means for opening said clearance chamber to the cylinder for partly unloading the head end of the cylinder, a by-pass port, pressure operated means for opening said by-pass port to said clearance chamber for further unloading of the head end of the cylinder, and pressure operated means for opening said by-pass port to the crank end of 55 the cylinder for wholly unloading the cylinder. 60

In testimony whereof I affix my signature.

MICHAEL RIESNER.
